UNITED STATES PATENT OFFICE.

ALPHONSE FERNANDEZ, OF WASHINGTON, DISTRICT OF COLUMBIA.

WINDOW-CLEANING DEVICE.

1,376,195.

Specification of Letters Patent. Patented Apr. 26, 1921.

Application filed February 14, 1921. Serial No. 444,836.

To all whom it may concern:

Be it known that I, ALPHONSE FERNANDEZ, a subject of the King of Spain, residing at Washington, District of Columbia, have invented certain new and useful Improvements in Window-Cleaning Devices; and I do hereby declare the following to be a full, clear, and exact description of the invention, such as will enable others skilled in the art to which it pertains to make and use the same.

My invention relates to improvements in a window cleaning device and more particularly to a fountain window glass cleaning or scrubbing device having means for the reception of water or other liquid for washing the window glass and also means for catching and retaining the dirty water removed from the window glass during the process of washing and scrubbing the same.

The invention consists in the several features and in the construction, combination and arrangement of such features as more fully hereinafter described and claimed.

The object of the invention is to provide means for thoroughly washing and cleaning a window glass, catching and retaining the dirty water or other liquid as it is removed from the glass and also drying and polishing the glass and catching and retaining any residue of water which may have been left on the glass after the washing operation.

A further object is to provide means for containing the clean water or other liquid with which the window is to be cleaned or washed, feeding the water to the window glass and catching and retaining the dirty water or other liquid as it flows from the window glass and catching and retaining any dirty water which is removed from the glass during the operation of drying and polishing the same.

A further object is to provide a window glass cleaning device which is simple, inexpensive and durable in construction and convenient and easy to use.

Referring to the drawings:

Figure 1 is a central vertical sectional view of my invention.

Fig. 2 is a front view in elevation.

Fig. 3 is a detail sectional view of the sponge receptacle.

Fig. 4 is a detail sectional view of the drying and polishing device.

And Fig. 5 is a detail sectional view of a modified form of the moistening element receptacle.

In the drawings in which similar reference characters denote similar parts throughout the several views, 1 represents the window glass cleaner, 2 the liquid receiving reservoir or container, preferably made cylindrical in shape or form but which may be made of any other desired shape or contour, provided with end walls 3 and 4 and divided centrally by means of a longitudinal partition 5 into two compartments or chambers 6 and 7, the upper compartment 6 being for the reception of the clean water or other liquid for use in washing, scrubbing or cleaning a window glass and the lower compartment 7 being for use for the reception of the dirty water or other liquid removed from the window during the operation or process of cleaning or scrubbing the same and 8 is a suitable handle for manipulating the device.

The upper compartment 6 of the reservoir is provided with a hollow rectangular longitudinally extending projection 9 in which a rectangular longitudinally extending moistening element or sponge receptacle 10 is mounted having a series of apertures 11 serving to feed the clean water from the upper compartment 6 to the moistening element or sponge 12.

Just below the moistening element or sponge receptacle an upwardly projecting longitudinal lip 13 is provided having a slot 14 with a strip of rubber 15 mounted therein and between the sponge receptacle and lip a longitudinally extending dirty water receiving recess or mouth 16 is formed which together with the rubber strip 15 catches the dirty water as it flows from the window glass and sponge and directs it into the lower dirty water receptacle 7 through a rectangular opening or inlet 17.

After the window glass has been thoroughly scrubbed, washed and cleaned the device is turned around by means of the handle 8 and the glass dried and polished by the rubbers 18 and 19.

The upper rubber 18 is made a little longer than the rubber 19 in order that the window cleaning device may be applied to the surface being operated upon in a substantially vertical position without pressing the lower rubber with too great a pressure against such surface and both are mounted in a rec-

- tangular frame 20 which in turn is mounted in a rectangular recess or aperture 21 in the compartment 7 and is provided with a longitudinally extending central aperture 22 situated between the rubbers 18 and 19 through which the dirty water removed from the window glass during the final operation of drying and polishing passes into the dirty water compartment 7.
10. The clean water or other liquid is introduced into the compartment 6 through an opening 23 in the end wall of the reservoir and the dirty water is removed from the dirty water compartment 7 through an opening 24 also in the end wall of the reservoir and each of the openings are provided with a cap or closure 25.

In the modified form of moistening holder shown in Fig. 5 holes 26 are formed in the liquid receiving reservoir or container, and a moistening element holder 27 is provided having holes 28, and 29 represents a piece of felt which is placed around and covers the receptacle 2, such felt being preferably tubular in form.

It will be seen that by the use of my invention a very simple and efficient window cleaning device has been produced which is formed so as to allow clean water to be discharged from one compartment of the reservoir so as to be conveyed to a pane of glass whereupon the moistening device or sponge carried by the reservoir may remove the filth and dirt from the window pane at which time the dirty water will be directed downwardly and will be caught so as to be conveyed into the interior of the dirty water receiving compartment. In this manner, it will be seen that a window may be easily cleaned while the water conveyed and discharged thereon may positively be caught so that when the window has been washed the dampness will be removed therefrom with-

out the necessity of employing rags or other cleaning devices for mopping the water and dampness from the pane of glass.

I do not wish to be understood as limiting myself to the specific details of construction and arrangement as herein described and illustrated, as it is manifest that variations and modifications may be made in the features of construction and arrangement in the adaptation of the device to various conditions of use without departing from the spirit and scope of my invention and improvements. I, therefore reserve the right to all such variations and modifications as properly fall within the scope of my invention and the terms of the following claims.

What I claim is:—

1. In a window cleaning device, a casing having upper and lower compartments, the upper compartment providing a reservoir for cleaning liquid, a moistening and cleaning element mounted upon and communicating with said reservoir, a trough with an inclined bottom extending from the lower compartment below said element, an opening into said lower compartment being provided above said bottom, and a resilient strip carried by the front edge of said bottom.

2. In a window cleaning device, a casing having a compartment providing a receptacle for liquid, and having a slot extending horizontally along one side, a frame mounted in said slot and having a slot at substantially the center thereof communicating with said compartment, and resilient strips mounted above and below the said central slot.

In testimony whereof I have affixed my signature.

ALPHONSE FERNANDEZ.
